Wahl Professional 5Star Shaver, 1 page, www.amazon.com, reviewed as early as <https://www.amazon.com/Wahl-Professional-5-Star-Rechargeable-8061-100/dp/B01EG4G7BQ> (Year: 2018).*

Primary Examiner — Jennifer Rivard(74) *Attorney, Agent, or Firm* — Greer, Burns & Crain, Ltd.(57) **CLAIM**

The ornamental design for a shaver, as shown and described.

DESCRIPTION

FIG. 1 is a top perspective view of a first embodiment of the present shaver;

FIG. 2 is a left side view of same;

FIG. 3 is a right side view of the shaver of FIG. 1;

FIG. 4 is a front view of same;

FIG. 5 is a rear view of the shaver of FIG. 1;

FIG. 6 is a top view of same; and

FIG. 7 is a bottom view of the shaver of FIG. 1;

FIG. 8 is a top perspective view of a second embodiment of the present shaver;

FIG. 9 is a left side view of same;

FIG. 10 is a right side view of the shaver of FIG. 8;

FIG. 11 is a front view of same;

FIG. 12 is a rear view of the shaver of FIG. 8;

FIG. 13 is a top view of same; and,

FIG. 14 is a bottom view of the shaver of FIG. 8.

The broken lines illustrate portions of the shaver and form no part of the claimed design.

1 Claim, 10 Drawing Sheets
